UNITED STATES PATENT OFFICE.

ADOLF GUND, OF NEW YORK, N. Y.

ANIMATED TOY.

1,032,205.

Specification of Letters Patent.

Patented July 9, 1912.

Application filed January 19, 1912. Serial No. 672,029.

To all whom it may concern:

Be it known that I, ADOLF GUND, a subject of the Emperor of Germany, and a resident of the city of New York, borough of the Bronx, in the county and State of New York, have invented a new and Improved Animated Toy, of which the following is a full, clear, and exact description.

The invention relates to wheeled toys, and its object is to provide a new and improved animated toy which simulates an animal, such as a dog, duck or the like, and when drawn over the floor moves certain members and at the same time emits sounds similar to those emitted by the animal simulated.

For the purpose mentioned use is made of a body provided with a movable member, a sound producer within the said body and having a movable actuating member, wheels, shafts journaled on the under side of the said body and carrying the said wheels, one of the said shafts being provided with a crank arm, a link within the said body and connecting the said crank arm with the said movable body member, and a rod attached to the said movable actuating member of the sound producer, the said rod having a slotted head engaging the said crank arm.

A practical embodiment of the invention is represented in the accompanying drawings forming a part of this specification, in which similar characters of reference indicate corresponding parts in both views.

Figure 1 is a longitudinal section through a stuffed toy duck, which embodies one form of my invention; and Fig. 2 is a cross section of the same.

The animated toy, as shown, is in the form of a stuffed bird, such as a duck, and the toy is provided with a stuffed body A containing a frame B, stuffing material C and a cover D of a fabric material. The frame B is arranged in the lower or bottom portion of the stuffed body A and to the front end of the said frame B is secured a vertical tube E extending upward through the neck A' of the body A and terminating in the head A''. The core A³, of wood or other material, for the upper jaw or bill A⁴ is attached to the top of the tube E, and the core A⁵, of wood or like material, for the lower jaw or bill A⁶ is pivoted on the core A³, and from the inner end of this core A⁵ extends rearwardly an arm or a rod A⁷ passing into the tube E by way of a slot E' arranged in the front upper

portion of the tube E. On the under side of the frame B are secured front and rear bearings F and F' extending through the bottom portion of the cover D, and the said bearings F and F' are journaled in the front and rear shafts or axles G, G' carrying wheels H, H' adapted to travel on the floor. The front shaft G is provided with a crank arm G² engaged by a link I extending up through the tube E and connecting with the extension arm or rod A⁷ of the core A⁵ of the lower jaw or bill A⁶, and hence when the shaft G is rotated an up and down swinging motion is given to the lower jaw or bill A⁶ by the connection just described.

The frame B is approximately of inverted V shape in cross section, thus providing a recess at the under side, and in this recess is fitted and secured to the frame B a sound producer J, of any approved construction, arranged to produce sounds similar to those emitted by the animal simulated. The sound producer J is provided with a movable actuating member J' adapted to swing up and down and carrying at its forward end a rod K terminating in a slotted head K' engaging the crank arm G², so that when the shaft G is rotated an up and down swinging motion is given by the crank arm G² to the slotted head K' and hence to the movable actuating member J' of the sound producer to cause the latter to emit sounds corresponding to those of the animal simulated.

When the animated toy is drawn forward over the floor or other support the wheels H, H' are rotated and consequently the shafts or axles G, G' whereby the crank arm G² imparts an up and down movement to the link I so that the latter swings the jaw or bill A⁶ down and up, and at the same time the crank arm G² imparts an up and down swinging motion to the rod K whereby the movable member J' of the sound producer is actuated and the latter emits sounds similar to those emitted by the animal simulated by the toy. In practice, the parts are so arranged that when the jaw or bill A⁶ swings downward sounds are produced. By arranging the frame B in the manner described the sound producer J is protected from the stuffing C to insure proper action of the sound producer in the manner described.

Having thus described my invention, I

claim as new and desire to secure by Letters Patent:

1. An animated toy, comprising a body provided with a movable member, a sound producer within the said body and having a movable actuating member, wheels, shafts journaled on the bottom of the said body and carrying the said wheels, one of the said shafts having a crank arm, a link within the said body and connecting the said crank arm with the movable member of the said body, and a rod attached to the movable member of the said sound producer, the said rod having a slotted head engaging the said crank arm independent of the said link.
2. An animated toy, comprising a body simulating an animal, the said body having a pivoted jaw provided with an inward extension, a frame within the body and provided with a tube extending in the neck of the said body, the said jaw being pivoted on the said tube, the said jaw extension extending into the tube, a sound producer within the said body and attached to the said frame, the said sound producer having a hinged actuating member extending approximately in a horizontal direction, wheels, shafts journaled on the said frame and carrying the said wheels, one of the said shafts having a crank arm, a link connected with the said crank arm and extending upward through the said tube, the upper end of the link being connected with the extension of the said pivoted jaw, and a rod attached to the said movable member of the

said sound producer and provided with a slotted head engaging the said crank arm independent of the said link.

3. An animated toy, comprising a stuffed body simulating an animal and provided with a fixed upper jaw and a lower pivoted jaw, the latter having an inwardly-extending arm, a frame within the said stuffed body and provided at the under side with a recess, the said frame being provided with a tube and extending upward through the neck of the said body, the tube carrying the said fixed jaw and the said pivoted jaw arm extending into the said tube, a sound producer attached to the said frame and arranged within the said recess, the sound producer having a rod terminating in a head having an elongated slot, wheels, shafts journaled on the under side of the said frame and carrying the said wheels, one of the shafts being provided with a crank arm, and a link connected with the said crank arm and extending up through the said tube, the upper end of the link being connected with the arm of the said pivoted jaw, the said crank arm being engaged by the said slotted head.

In testimony whereof I have signed my name to this specification in the presence of two subscribing witnesses.

ADOLF GUND.
